DESIGN FOR A BUCKLE

Louis Alterson, New York, N. Y.

Application August 18, 1936, Serial No. 64,468

Term of patent 3½ years

To all whom it may concern:

Be it known that I, Louis Alterson, a citizen of the United States of America, residing in the city of New York, county of New York, and State of New York, have invented a new, original, and ornamental Design for a Buckle, of which the following is a specification, reference being had to the accompanying drawing, forming part thereof,

Fig. 1 is a front view of a buckle showing my new design.

Fig. 2 is a plan view of a buckle as shown in Fig. 1.

I claim:

The ornamental design for a buckle substantially as shown.

LOUIS ALTERSON.
